DESIGN FOR A TRANSLUCENT REFLECTOR FOR ELECTRIC LIGHTING FIXTURES

George Ainsworth, New York, N. Y.

Application April 2, 1936, Serial No. 61,906

Term of patent 14 years

To all whom it may concern:

Be it known that I, George Ainsworth, a citizen of the United States, residing in New York, in the county of New York and State of New York, have invented a new, original, and ornamental Design for a Translucent Reflector for Electric Lighting Fixtures, of which the following is a specification, reference being had to the accompanying drawing, forming part thereof.

Fig. 1 is a side elevational view of a translucent reflector for electric lighting fixtures showing my new design; and

Fig. 2 is a bottom plan view, thereof.

I claim:

The ornamental design for a translucent reflector for electric lighting fixtures, substantially as shown.

GEORGE AINSWORTH.
